I. KIDDER

CANDY BOX

Filed Feb. 14 1927

INVENTOR.

Imogene Kidder

UNITED STATES PATENT OFFICE.

IMOGENE KIDDER, OF PORTLAND, OREGON.

DESIGN FOR A CANDY BOX.

Application filed February 14, 1927. Serial No. 20,757. Term of patent 3½ years.

To all whom it may concern:

Be it known that I, IMOGENE KIDDER, a citizen of the United States, residing at Portland, in the county of Multnomah and State of Oregon, have invented a new, original, and ornamental Design for a Candy Box, of which the following is a specification, reference being had to the accompanying drawing, forming part thereof.

The figure is a front view of a candy box, showing my new design.

I claim:

The ornamental design for a candy box, as shown.

IMOGENE KIDDER.
